CLAIM

The ornamental design for an exercise disc with casters, as shown and described.

DESCRIPTION

FIG. 1 is a perspective view of the exercise disc with casters of the present invention;

FIG. 2 is a top view of the exercise disc with casters shown in FIG. 1;

FIG. 3 is a bottom view of the exercise disc with casters shown in FIG. 1; and,

FIG. 4 is a side view of the exercise disc with casters shown in FIG. 1.

Any broken line illustration of environmental structure in the drawings is not part of the claimed design.
